MINE CAR LATCH ASSEMBLY

Herman H. Pancake, Huntington, W. Va., assignor
to American Car and Foundry Company, New
York, N. Y., a corporation of New Jersey

Application December 16, 1943, Serial No. 514,467

14 Claims. (Cl. 214—58)

1

This invention relates to latches in general and in particular to latches for use on drop bottom mine cars.

Nearly all drop bottom mine cars built in the past have been controlled by means of a single lever pivoted at the end wall of the car and formed with a hook engaging a door lug at the rear central portion of the last door. In order to operate the latch arm trackside means was provided to lift the latch. This of necessity required the latch to project beyond the side wall of the car. Due to the projection of the latch arm beyond the side wall the arm was frequently bent in service, with the result that the doors could not be unlatched until the arm was straightened. At other times the latch arm would engage trackside obstructions and trip the doors thus tying up the track and preventing movement of any cars until the dropped doors had been jacked into closed position. Frequently the car had to be unloaded before the doors could be raised. It is an object, therefore, of the present invention to provide a drop bottom car with a latch assembly having the parts so arranged as to remain at all times wholly within the clearance limits of the car.

A further object of the invention is the provision of a latch mechanism for drop bottom mine cars, which mechanism can be operated only by means of special trackside tripping means.

A still further object of the invention is the provision of a drop bottom mine car having the latch assembly operated by a trip lever carried and protected by the side sills adjacent their ends.

These and other objects of the invention will be apparent to persons skilled in the art from a study of the following description and accompanying drawings, in which

Figure 1 is an elevational view of the rear end of the car but with parts broken away to better disclose the latch assembly;

Fig. 2 is an end view of the construction of Fig. 1 with parts broken away to disclose the construction;

Fig. 3 is a sectional view taken substantially on line 3—3 of Fig. 2;

Fig. 4 is a plan view of the end of the sill shown in Fig. 1;

Fig. 5 is a view similar to Fig. 2 but showing a slight modification in the hook form;

Fig. 6 is an elevational view similar to Fig. 1 but showing a slight modification of the sill and latch assembly;

Fig. 7 is an end view of the construction of Fig.

2

6 with parts broken away to disclose the assembly;

Fig. 8 is a plan view of the sill construction of Fig. 7;

Fig. 9 is an elevational view showing a still further slight modification in latch assembly;

Fig. 10 is an end view of the construction of Fig. 9;

Fig. 11 is an elevational view similar to Fig. 9 but showing a slight modification thereof, and

Fig. 12 is an end view of the construction shown in Fig. 11.

Referring now to the drawings in detail, it will be seen that the car body construction disclosed in the various figures is identical as is also certain other parts of the construction dealing with the latch assembly. Accordingly, wherever possible the same reference numerals will be used to refer to identical parts in the various figures. As

clearly shown the car is constructed with spaced side sills 2 to which are connected the sloping side walls 4, joined together by end walls 6. The space between the side sills is adapted to be closed by one or more doors 8 pivoted to swing about an axis extending transversely of the car. The car body is supported on axles which in turn are supported by wheels W resting on rails R forming the track upon which the cars run. The side sills, as clearly shown, are of angle form adjacent their ends and have attached thereto end sill structures S which include bumpers B and draft means D. As shown the side sills are formed with a bottom outwardly directed horizontal flange 10, which extends from end to end of the sill, and with an inclined top flange 12 which extends more or less continuous from end sill structure to end sill structure.

In order to release the various latch assemblies, later to be described, a special trackside trip T is provided as clearly shown in Figs. 1, 2, 6, 7 and 9 to 12 inclusive. This trackside trip is formed with an upwardly open U-shaped base member 18 welded or otherwise secured to a strap 20 pivoted as at 22 to a supporting base 23. The U-shaped

base member is provided with spring seats adapted to receive and support the lower ends of springs 24, the upper ends of which bear against spring seats carried by a vertically movable housing member 26. The sides of this housing member are formed with elongated slots 28 permitting vertical movement of the housing relative to securing bolts 30 extending through the arms of the base member. The sides of the housing are also provided with openings through which a pin 32 may extend to support a roller 34. It will thus be

seen that the roller 34 is free to rotate about its axis, and may move vertically relative to the base structure under control of the springs 24. The slots 28 are of sufficient length to permit downward movement of the housing and roller so that the bottom flange 10 of the side sills may move across the trip device without danger of breaking the trip member. In order to permit passage of cars past the dumping station without tripping the latches the trip roller assembly may be swung to one side about pivot 22, as clearly shown in Fig. 2. In some cases it may be desirable to relieve the latches of load strain during the tripping operation and this may be done by use of broad rollers 36 (Fig. 2), which rollers will lift the doors slightly taking the strain off of the latch member.

The latch assembly, as shown in Figs. 1 to 4 inclusive, comprises a hook member 40, pivoted as at 41 within a housing 42 carried by the end sill structure and end wall of the car. The hook extends downwardly to releasably engage the door lug L. In order to urge the hook toward latched position a plunger 44 is provided which has sliding engagement in a bracket 45 carried by the end structure and serving as an abutment for compression spring 46 constantly urging the hook toward latched position. Also connected to the hook is a tension rod 48 which in turn is pivotally connected to the lower end of arm 49 of a bell crank member 50. The intermediate portion of this bell crank member is pivotally connected as at 51 to upstanding ears or lugs 52 welded or otherwise secured to the end sill structure. The remaining arm of the bell crank member has pivotally connected thereto as at 53 a pusher rod 54. The lower end of this pusher rod engages within a pocket 55 formed in the rear or free end of a trip lever 56 pivoted as at 57 to the side sill structure. In order that the roller 34 of the trackside trip may engage the trip lever a slot 58 is cut or otherwise formed in the flange 10 of the side sill. To restore the sill to its full strength, while at the same time housing the trip lever, a plate 59 is welded or otherwise secured to the outer edge of the sill flange and to the sill web. Also a stiffening plate 60 is welded to the flanges and web of the sill as well as to housing plate 59. In this manner the trip lever is fully enclosed within a box-like formation at the end of the sill and can be reached only by means projecting into the slot 58. It will be seen that during movement of the car the roller 34 may engage trip lever 56 and cause a lifting of the trip lever. Lifting of the trip lever will cause rotation of the bell crank, which in turn will cause release of the hook from the door lug.

At times it may be desirable to utilize a more positive latching arrangement than shown in Figs. 1 to 4 and this may be accomplished through the use of the construction shown in Fig. 5. In this arrangement the construction of Figs. 1 to 4 has been duplicated, but in addition a second hook 62 has been added and which pivots around pivot 41. The upper end of this added hook is extended and pivotally connected to a second tension rod 63, which in turn is pivoted to the arm 49 of the bell crank member 50. In this form the operation by the trackside roller is the same as in Figs. 1 to 4 but the swinging of the bell crank 50 will, through rods or links 48 and 63, cause a swinging of hooks 40 and 62 in opposite directions to release lug L.

In some cases it may be necessary, due to clearance limitations or danger of damage to bell crank 50, to reverse the position of the same.

Accordingly, the reversed construction has been shown in Figs. 6, 7 and 8. Since the hook, operating rod or link and spring urged plunger construction is substantially the same as shown in Figs. 1 to 5 inclusive, the same reference numerals have been applied thereto to identify the same parts. In this form the bell crank is pivoted as at 64 within the vertical limits of the end sill structure and the arm 65 of the bell crank extends outwardly through a slot 66 cut in the end of the side sill. By this arrangement the arm may be directly connected to the free end of a trip lever 68 swingable about a pivot pin 69 carried by the sill and by reinforcing plate 70 welded or otherwise secured to the outer edges of flanges 10 and 12 of the sill. In this form the trip lever is not fully housed as in Figs. 1 to 5, but the slot 58 cut in the sill is compensated for partially by the plate 70 and also by bracing and control plates 72 welded to the lower flange and web of the sill and inclined upwardly and outwardly toward the end of the car and toward pivot 69. These bracing and control plates assist in easing the roller 34 into contact with trip lever 68 as the car moves across the spring urged roller 34.

In certain cases it may be desirable to modify existing cars so as to take advantage of the improved construction. Accordingly, in Figs. 9 to 12 inclusive the more or less conventional door control arm has been shown. In these figures the door control arm 76 pivots on the end structure as at 77. This door control arm has attached thereto the hook 78 adapted to engage door lug L and be held in engagement therewith by compression spring 80. Normally, the door control arm 76 extends outwardly beyond the side wall of the car, but in the present case the end has been removed so that the arm is always within the clearance limits of the car as defined by the side walls. To the free end of the door control arm is pivoted as at 81 a pusher rod 82, which in turn has its lower end pivoted to the free end of a trip lever 84 pivotally carried by the sill and located above the slot 58 cut in the flange 10. The pivotal connection of the trip lever 84 to the side sill, as well as the bracing of the side sill of Figs. 9 and 10, is identical with that described in connection with Figs. 6, 7 and 8 and accordingly the same reference numerals have been applied.

It may be desirable to eliminate the guiding and bracing plates 72 and permit a more gradual engagement between the roller 34 and trip lever 84. This may be accomplished as shown in Figs. 11 and 12 by pivoting the lever 84 on a pin 88 located forwardly of the forward end of slot 58. In this way the roller 34 will contact the trip lever 84 immediately upon entering the slot 58.

It is believed that the operation of the various forms of latch assemblies will be obvious from the preceding description. However, a general description of this operation may be helpful. The cars as they move toward and over the dumping station will contact the roller 34 and move the same downwardly against the compression of springs 24. Continued forward movement of the car in the direction indicated by the arrows in Figs. 1, 6, 9 and 11 will cause the roller 34 to roll along the bottom surface of flange 10 of the side sill. As soon, however, as the roller reaches the forward end of slot 58 it will move upwardly under action of springs 24 and lift the trip lever. Lifting of the trip lever will, of course, cause an un-

latching movement of the door supporting hook thereby releasing the door. In some operations the empty cars are returned over the dumping station and this will require that the tripping member be rotated to the line and dash position of Figure 2 about the pivot 22. Such movement of the tripping member will also permit passage of cars containing rock or slate, in other words, a selective dumping of the cars. The constructions of Figs. 1 to 8 inclusive may be applied to existing cars without a major change, but the construction of Figs. 9 to 12 may be applied with a minimum of change to the existing cars. For this form it is only necessary to cut off the operating arm, slot the sill lower flange and reinforce the sill, then the trip lever and pusher rod may be connected to the sill and arm respectively.

Although the latch assembly has been described more or less in detail with specific reference to the drawings, it will be obvious that various modifications and rearrangements of parts, other than those shown and described, may be made and all such modifications and rearrangements of parts are contemplated as fall within the scope of the appended claims defining my invention.

What is claimed is:

1. In a drop bottom mine car having load retaining side walls and side sill members, a drop bottom door hingedly carried by the car, and a latch assembly carried by the car and including a part mounted for swinging movement transversely of the car and normally engaging the door to retain the same in raised position and movable to release the door for opening, said latch assembly also including an operator part carried by a side sill member and extending longitudinally of the car and located wholly within the area defined by the outermost boundary planes of the side sill member.

2. In a drop bottom mine car having load retaining side walls and side sill members, a drop bottom door hingedly carried by the car, and a latch assembly carried by the car and including a part mounted for swinging movement transversely of the car and normally engaging the door to retain the same in raised position and movable to release the door for opening, said latch assembly also including an operator part carried by a side sill member and extending longitudinally of the car and located wholly within the area defined by the outermost boundary planes of the side sill member, and said operator part and sill member being so constructed and arranged so that said operator part may be moved by trackside means projecting into said area.

3. In a drop bottom mine car having load supporting sill members joined by end sills, a drop bottom door hingedly carried by the car, a latch assembly carried by the car and having a part normally engaging the door to retain the same in raised position and movable to release the door for opening, said assembly including a latch hook mounted for swinging movement transversely of car, latch hook operating means extending transversely of the car and connected to the latch hook, and a trip lever pivotally carried by a load supporting sill member and engaging said latch hook operating means to move the same for release of the door, said trip lever being located on the load supporting sill member wholly within the area defined by the outermost boundary planes of the load supporting sill member.

4. In a drop bottom mine car having load supporting sill members joined by end sills, a drop

bottom door hingedly carried by the car, a latch assembly carried by the car and having a part normally engaging the door to retain the same in raised position and movable to release the door

5 for opening, said assembly including a latch hook, a link connected to said latch hook, a bell-crank carried by one of the end sills and connected to said link, a trip lever pivotally mounted on one of the side sills, and means interposed between said trip lever and bell-crank for transmitting motion therebetween.

5. In a drop bottom mine car having load supporting sill members joined by end sills, a drop bottom door hingedly carried by the car, a latch assembly carried by the car and having a part normally engaging the door to retain the same in raised position and movable to release the door for opening, said assembly including a latch hook, a link connected to said latch hook, a bell-crank connected to said link and carried by one of the end sills and located between the horizontal planes defining the sill and a trip lever pivotally mounted on one of the side sills and operatively connected to said bell-crank to operate the same.

20 6. In a drop bottom mine car having load supporting sill members joined by end sills, a drop bottom door hingedly carried by the car, a latch assembly carried by the car and having a part normally engaging the door to retain the same in raised position and movable to release the door for opening, said assembly including a latch hook, means connected to said latch hook and extending transversely of the car and being carried by one of the end sills between the horizontal planes defining the sill, a trip lever pivotally mounted on one of the side sills for swinging movement in the vertical plane of the sill, and means connecting said trip lever and first named means.

25 7. In a drop bottom mine car having load supporting sill members joined by end sills, a drop bottom door hingedly carried by the car, a latch assembly carried by the car and having a part normally engaging the door to retain the same in raised position and movable to release the door for opening, said assembly including a latch hook, a trip lever pivotally mounted on one of the side sills for swinging movement in the vertical plane of the sill, and means connecting said trip lever and latch hook for joint operation.

30 8. In a drop bottom mine car having flanged load supporting sill members supported by flanged wheels, a drop bottom door hingedly carried by the car, a latch assembly also carried by the car and having a part normally engaging the door to retain the same in raised position and movable to release the door for opening, said assembly including a latch hook, and means pivotally carried by one of the sills above a slot in the lower flange and being connected to said latch hook for moving the same to release the door, said means being operable by trackside means projectable through the slot in the sill lower flange.

35 9. In a drop bottom mine car having flanged load supporting sill members supported by flanged wheels, a drop bottom door hingedly carried by the car, a latch assembly also carried by the car and having a part normally engaging the door to retain the same in raised position and movable to release the door for opening, said assembly including a latch hook, and means pivotally carried by one of the sills above a slot in the lower flange and being connected to said latch hook for moving the same to release the door, said means being operable by trackside means projectable through

the slot in the sill lower flange, and said assembly being located wholly between the planes of the wheel flanges.

10. In a drop bottom mine car having flanged load supporting sill members supported by flanged wheels, a drop bottom door hingedly carried by the car, a latch assembly also carried by the car and having a part normally engaging the door to retain the same in raised position and movable to release the door for opening, said assembly including a latch hook, and means pivotally carried by one of the sills above a slot in the lower flange and being connected to said latch hook for moving the same to release the door, said means being operable by a trackside device located between the rails of the track and projectable through the slot in the sill lower flange.

11. In a drop bottom mine car assembly the combination with a car having flanged side sills carried by flanged wheels rolling on rails, of a drop bottom door hingedly carried by the car, a latch hook also carried by the car and normally engaging the door to retain the same in raised position and movable to release the door for opening, operating means connected to said latch hook and including a trip lever carried by the car above a slot in the lower flange of one of said side sills, and vertically movable means independent of the car for operating said trip lever, said vertically movable means being located between the rails and projectable through said slot to operate said trip lever.

12. An article of manufacture for drop bottom mine cars having flanged load supporting sills and a drop bottom door controlled by a latch hook and latch arm comprising, a trip lever adapted to be pivotally connected to a load supporting sill above a slot therein for operation by trackside means projectable through the slot, and means pivotally connected to said trip lever and adapted to be connected to the latch arm for joint operation.

13. In a drop bottom mine car having load retaining side walls and side sill members, a drop bottom door hingedly carried by the car, and a latch assembly carried by the car and including a part mounted for swinging movement trans-

versely of the car and normally engaging the door to retain the same in raised position, said latch assembly also including an operator part carried by a side sill member and extending longitudinally of the car, said operator part being operatively connected to said first-named part and movable to release the door for opening, said latch assembly in its entirety being located at all times wholly within the outline of the car as defined by the side walls, door and vertical planes of the side sill members.

14. In a drop bottom mine car having load supporting sill members joined by end sills, a drop bottom door hingedly carried by the car, a latch assembly carried by the car and comprising a latch hook normally engaging the door to retain the same in raised position and movable to release the door for opening, latch hook operating means connected to said latch hook carried by an end sill and extending transversely of the car, tripping means for said latch hook operating means carried by a load supporting sill member and extending longitudinally of the car, and means operatively connecting said tripping means and said latch hook operating means.
